United States Patent Office

Des. 181,987
Patented Jan. 28, 1958

181,987

HEADBOARD OR THE LIKE

John J. Lubberts and Lambert J. Mulder, Grand Rapids, Mich., assignors to Tomlinson of High Point, High Point, N. C., a corporation of North Carolina

Application March 8, 1957, Serial No. 45,152

Term of patent 14 years

(Cl. D5—4)

FIG. 1

We claim:

The ornamental design for a headboard or the like, substantially as shown.
